WAVEGUIDE SWITCH

Gershon J. Wheeler, Newton Center, and Chester P. Williams, Waltham, Mass., assignors, by mesne assignments, to the United States of America as represented by the Secretary of the Navy

Application December 16, 1955, Serial No. 553,669

1 Claim. (Cl. 333—7)

The present invention relates to a novel and improved switching device for waveguide radiation apparatus and more particularly to a novel and improved waveguide switch which is relatively simple in construction and yet reliable and effective in operation.

In the transmission of high frequency energy through waveguide systems, it often becomes necessary and desirable to direct the energy from a given source through one or another of a series of output circuits. Thus, for example, where it is desired to use a common antenna array for the receiving and the transmitting circuits of high frequency electronic gear, the antenna circuit must be adapted for selective connection with the transmitter or the receiver. Since waveguides are often used to couple the antenna with the transmitter and receiver equipment, the need for a suitable waveguide switch arose. Although various types of waveguide switches have been used in the past, considerable difficulty has been experienced heretofore in devising a switch of this type which is reliable and dependable in operation.

It is a principal object of the present invention to provide a novel and improved waveguide switch that may be used to selectively feed or receive energy from one waveguide into either of a pair of waveguide output or energy drive circuits.

It is a further object of the present invention to provide a novel and improved waveguide switch having no measurable attenuation and no measurable leakage into the disconnected output circuit.

Other objects and many of the attendant advantages of this invention will be readily appreciated as the same becomes better understood by reference to the following detailed description when considered in connection with the accompanying drawing wherein:

Figure 1 is a front elevational view of a preferred embodiment of the present invention.

Figure 2 is a side elevational view partly in section of the embodiment shown in Figure 1.

Figure 3 is a perspective view of the switch block of Figures 1 and 2.

Figure 4 is a preferred schematic wiring diagram of the electric motor of Figures 1 and 2.

A preferred embodiment of the present invention is illustrated in Figures 1 to 4 of the drawing. As shown therein, the electric motor or the like 3 is mounted on and secured to the inverted T-shaped frame member 4 in any suitable conventional manner. The shaft 5 which rotates with the armature of the motor 3 extends through the aperture 6 in the upright portion 4a of the frame and is preferably supported therein by the bearing members or the like 7. The elliptical shaped cam element 8 is mounted adjacent the outer extremity of the shaft 5 and is coupled by means of the crank pin 9 and the connecting lever 10 to the vertically movable rod 11 and the switch block assembly 12. The oppositely deflected leaf-type spring members 13 and 14 which are secured to the end of rod 11 cooperate with the U-shaped lugs

2

15 that project downwardly from the switch block 16 to provide a spring loaded type of interconnection in a manner which will be more apparent hereinafter. As will also be more apparent hereinafter, the limit switch mechanism 17 secured to support member 4 provides automatic deenergization of motor 3 when full operation of the switch into its newly selected position is completed.

The receptacle or housing 18 to which the various waveguides 19, 20 and 21 are connected is secured in any 10 suitable conventional manner preferably adjacent the upper extremity of the support member 4. The switch block 16 through which the straight rectangular waveguide coupling section 16a and the curvilinear coupling section 16b extend is adapted to move vertically in the opening 22 through the housing 18 between predetermined switch terminal positions. In this way as will be more apparent hereinafter the straight and curvilinear coupling sections 16a and 16b are adapted to register properly with the openings in the housing 18 at the junction of waveguides 19, 20 and 21 therewith. The bearing plate 23 is preferably spaced from the lower surface of the housing 18 by the stove bolts or the like 24 and as will be more apparent hereinafter provides a journal for the vertical reciprocal movement of rod 11 therein. 15 The stop members 25 disposed on the upper surface of the housing 18 and the pad elements 26 on the U-shaped lugs 15 allow proper alignment of the straight and curvilinear coupling sections of the switch block 16 with the adjacent waveguides 19, 20 and 21 when the switch occupies either of its terminal positions.

In operation, when the switch block assembly 12 occupies the position shown in Figures 1 and 2 of the drawing, energy from any suitable energy source coupled to waveguide 19 is delivered therefrom through the curvilinear coupling section 16b of the switch block assembly to the waveguide 20 and to the output circuit to which waveguide 20 may be coupled. When it is desired to feed energy from waveguide 19 to the output circuit coupled to waveguide 21 through the straight coupling section 16a of the switch block, the motor 3 is energized by any suitable conventional starting switch mechanism. As the armature of motor 3 turns over, the cam 8 is rotated from point 8a on its periphery 180 degrees to point 8b and the rod 11 and the switch block assembly 12 is elevated to its uppermost position where the switch block is spring biased against the stop elements 25 by the leaf spring element 14. In this position the straight coupling section of the switch block electrically interconnects waveguide 19 with waveguide 21.

As is best shown in Figure 4 of the drawing, once the starting switch 27 for the motor 3 is activated and the elliptical-shaped cam 8 allows the contacts of switch 28 to close, the motor 3 remains energized until the cam rotates a half revolution and switch 28 is again opened. In this way the motor 3 is automatically deenergized when the waveguide switch has been fully operated to either of its terminal positions.

It is to be understood that although the waveguide switch of the present invention has been disclosed and described as a device for selectively directing energy from a given energy source to either of a pair of waveguide output circuits, a waveguide switch having two or more coupling sections in its switch block could be used to selectively interconnect a plurality of electrical circuits in any suitable way such as by coupling a pair or more of energy sources to a given output circuit without departing from the spirit or scope of the present invention.

Obviously many modifications and variations of the present invention are possible in the light of the above teachings. It is therefore to be understood that within

the scope of the appended claim the invention may be practiced otherwise than as specifically described.

What is claimed is:

Apparatus for selectively coupling a first waveguide with either a second or a third waveguide comprising a housing having a cavity to which each of the said waveguides is coupled; a switch block which is slideably adjustable in a vertical plane within the cavity and which has a straight waveguide section and a curvilinear waveguide section that extend through the switch block; an electric motor; and means responsive to energization of the motor for causing movement of the switch block between a first terminal position where the straight waveguide section completes a circuit between the first and second waveguides and a second terminal position where its curvilinear waveguide completes a circuit between the first and third waveguides; means including leaf spring

elements to allow proper alignment of the straight and curvilinear coupling sections of the switch block with the adjacent waveguides when the switch block occupies either of its terminal positions; and limit switch means for automatically deenergizing the motor when movement of the switch block into either its first or its second position is completed.
